TO OTIS BED MFG. COMPANY, OF BUFFALO, NEW YORK, A CORPORATION OF NEW
YORK.

FEATHER RENOVATOR.

Application filed November 5, 1921. Serial No. 513,115.

To all whom it may concern:

Be it known that we, HARVEY A. CHADWICK and ROBERT A. GREENE, citizens of the United States, residing at Buffalo, in the county of Erie and State of New York, have invented new and useful Improvements in Feather Renovators, of which the following is a specification.

This invention relates to an apparatus for 10 renovating and sterilizing the feathers of pillows and mattresses.

Its chief object is the provision of an efficient machine of this character by which feathers can be thoroughly disinfected, purified and dried in a comparatively short time.

A further object is to so organize the apparatus that the feathers, after being renovated and dried, may be delivered either 20 into receiving bins or directly into ticks or cases, without being handled, rendering them absolutely clean and sanitary and keeping them light and fluffy.

In the accompanying drawings: Figure 25 1 is a side elevation of the apparatus. Figure 2 is a longitudinal section thereof. Figure 3 is a rear view thereof. Figure 4 is a transverse vertical section on line 4—4, Fig. 1. Figure 5 is a similar section on line 5—5, Fig. 1, on an enlarged scale. Figure 6 is 30 an enlarged horizontal section on line 6—6, Fig. 5. Figure 7 is a vertical section on line 7—7, Fig. 6. Figure 8 is a view similar to Fig. 7, showing the tick-filling nozzle applied to the discharge box. Figure 9 is a perspective view of said nozzle.

Similar characters of reference indicate corresponding parts throughout the several views.

40 10 indicates a housing or casing preferably of oblong form having a dome-like top 11 terminating in a central discharge flue 12 for the down of the feathers. This flue may be closed by a slide or valve 13. 45 In its side the housing has a manhole closed by a door 14. Supported lengthwise within the lower portion of the housing is a trough or open tank 15, preferably of semi-circular form. The upper part of the housing into which the tank opens constitutes a renovating and sterilizing chamber 16 and is separated by a diaphragm 17 from the lower part which contains the tank and constitutes a heating chamber 18 for the latter. 50 55 This chamber is heated by radiators 19 or

other suitable appliances which may be located beneath the tank and at its sides, as shown in Fig. 4.

Located within the apparatus is a perforated steam-delivery pipe 20 for thoroughly sterilizing and purifying the feathers, superheated steam being most suitable for this purpose. This pipe is preferably arranged lengthwise within the tank near its upper rear side and is provided outside 60 of the housing 10 with a hand valve 21.

A suitable agitator is arranged in the tank for keeping the feathers in constant motion and subjecting all portions thereof to the action of the steam. The preferred 70 device for this purpose consists of a longitudinal shaft 22 provided with agitator arms 23 extending radially therefrom, this shaft extending through one end of the housing 10 where it has a pulley 24 for 75 driving it. The arms 23 are preferably arranged spirally and so as to trend from both ends toward the center of the shaft. By this arrangement the feathers in all parts of the tank and the casing are kept in circulation and thoroughly subjected to the steaming process.

Leading into the housing near its upper end is an inlet conduit 25 for the feathers to be treated which is connected with a supply bin, not shown, this conduit having a suitable cut-off valve or slide 26. Communicating with the opposite end of the housing near its upper end is a suction conduit 27 leading to an exhaust box or chamber 28 which is in turn connected by a pipe 29 with the inlet of a fan 30 or other suitable current inducing means. The purpose of the conduit 27 is to draw the feathers to be treated through the inlet conduit 25 85 into the housing, thus avoiding handling of the feathers. Said suction conduit is provided with a valve 31 for regulating or cutting off the suction current from the housing.

At the rear end of its lower portion, the tank 15 is provided with a feather-outlet or tube 32 communicating with the exhaust box 28, for withdrawing the renovated and dried feathers from the tank, without handling them, as hereinafter more fully described. This outlet is controlled by a cut-off valve of slide 33 having a port 34 adapted to register with the outlet, to place it in communication with the exhaust box, this valve hav- 100 105 110

ing a hand lever 35 or other convenient means for operating it.

36 indicates a discharge box or case connected with the blast spout of the fan 30 and adapted to receive the renovated feathers therefrom, and 37 indicates a discharge conduit leading from said box to one or more receiving bins, not shown. Feathers are usually graded and collected in different bins, 10 and for this purpose a hollow distributing head or valve case 38 may be employed from which the various grades of feathers are conducted to such bins by separate pipes 39 connected to different sides of the valve case. The delivery of the feathers into the several bins is controlled by slides 40 or other appropriate valves.

In order to permit the renovated feathers to be discharged directly into pillow or mattress ticks without handling the feathers, the discharge box 36 is provided with an auxiliary outlet 41 normally closed by a door or valve 42 hinged at its lower edge to said box. Upon opening this door, there may be 25 applied to said outlet, a detachable spout 43 over which the ticks are successively slipped, as shown in Fig. 8, to fill them. The spout has a base flange 44 which is confined at its lower edge between the inner 30 edge of the open door 42 and the adjacent wall of the discharge box, the upper edge of the spout flange being secured in place by the same turn button 45 which keeps said door closed. To control the delivery of the 35 feathers into the ticks, the outlet is provided with a valve or slide 46.

As shown in Figs. 1, 5 and 6, the exhaust box 28 has a vent-opening 47 controlled by a valve or door 48, preferably hinged like 40 the door 42 of the discharge box. The valve is opened more or less, as required, to permit the necessary suction current for discharging the feathers from the housing and to prevent clogging of the discharge conduit 37.

Provision is also made for separately collecting the down or very small and light feathers. This consists of a hood 49 placed over the upper end of the flue 12, and an 50 auxiliary suction conduit or branch 50 leading from the top of the hood to the main suction conduit 27 and containing a controlling valve 51.

To conveniently gather up and collect any 55 feathers lying on the floor around the renovator, the removable spout 43 may be transferred to the auxiliary inlet 47 of the exhaust box, and a hose 52 attached to the spout, such outside feathers being discharged into 60 one of the receiving bins.

The operation of the apparatus is as follows:

The valve of the feather inlet-conduit 25, and the valve 31 of the main suction conduit 65 27 are opened, and the valve 33 of the feather

outlet tube, the damper 13 of the flue 12, and the valves 48, 42 of the exhaust and discharge boxes 28, 36 are closed. Upon setting the fan in motion, a suction current is created which draws the feathers to be 70 renovated through the inlet conduit 25 into the housing of the apparatus. After thus loading the renovator, the inlet and suction valves 26, 31 are closed, the fan is stopped, steam is admitted to the pipe 20, the agitator 75 arms are actuated and heat is supplied to the radiators 19. The feathers are subjected to the renovating and sterilizing action of the steam for a sufficient period, say about five minutes, the same being constantly kept 80 in motion by the agitator arms whereby all portions thereof are exposed to the steam and thoroughly treated. The steam is then turned off and the flue damper 13 opened to allow the vapor to escape from the housing, 85 after which the down and feathers are allowed to remain in the housing for about fifteen minutes to thoroughly dry them, the agitators being kept in motion to expedite this step. The fan is again started and the 90 down is next withdrawn from the renovator by opening the suction valve 51.

If the dried feathers are to be discharged into a given receiving bin, the corresponding valve 40 of the distributing head 38 is 95 opened together with the valve 33 of the suction outlet 32 of the tank, whereupon the feathers are withdrawn from the renovator by the fan and delivered into said bin.

When it is desired to fill pillow ticks or 100 mattresses with renovated feathers directly from the renovator, all the valves 40 of the distributing head 38 are closed, the filling spout 43 is applied to the auxiliary outlet 41 of the discharge box 36, as shown in Fig. 105 8, the tick is slipped over the spout, and the valve 33 of the suction outlet 32 opened, as before.

This improved apparatus thoroughly sterilizes, purifies and dries the feathers and renders them light and fluffy. This is accomplished in a comparatively short time and without the necessity of touching or handling the feathers which are drawn into and out of the renovator by the fan and delivered 110 by it either directly into the ticks or into receiving bins, as desired. The apparatus thus renders the renovating process perfectly 115 clean and sanitary from beginning to end.

By arranging the suction outlet 27 in the 120 upper part of the casing, as shown, the air current tends to lift the feathers or keep them in suspension to a certain extent. This lessens the resistance to the agitator and enables it to be actuated while loading the 125 machine, thus avoiding undue strain on the agitator shaft and saving time in renovating the successive charges or batches of feathers, by permitting them to be subjected at once to the steaming action.

We claim as our invention:

1. A feather renovator, comprising a treating chamber having a feather inlet, an outlet for a suction-current and a feather outlet, an exhaust device, and suction-conduits leading from said current outlet and said feather outlet to said exhaust device.
2. A feather renovator, comprising a treating chamber having a feather inlet in its upper portion, an outlet for a suction current located in the upper portion of the treating chamber opposite said feather inlet and a feather outlet located in the lower portion of said chamber, an exhaust device, and exhaust conduits leading from said current outlet and said feather outlet to said exhaust device.
3. A feather renovator, comprising a casing having a feather inlet, a tank arranged in the lower portion of said casing and having a feather outlet, an agitator located in said tank, means for delivering steam into said casing, and an exhaust device for drawing the feathers to be treated through said inlet into the casing and withdrawing the renovated feathers through said outlet.
4. A feather renovator, comprising a casing having a feather inlet, a tank arranged in the lower portion of said casing and having a feather outlet, an agitator located in said tank, a perforated steam delivery pipe arranged in the upper portion of said tank, and an exhaust device for drawing the feathers to be treated through said inlet into the casing and withdrawing the renovated feathers through said outlet.
5. A feather renovator, comprising a treating chamber having a feather inlet and a feather outlet, an exhaust device, a suction conduit leading from said feather outlet to said exhaust device, and an air box interposed in said conduit and having a valve-controlled air inlet.
6. A feather renovator, comprising a treating chamber having a feather inlet and a feather outlet, an exhaust device, a suction conduit leading from said feather outlet to the inlet of said exhaust device, and a discharge box connected to the outlet of said exhaust device and having a delivery opening.
7. A feather renovator, comprising a treating chamber having a feather-inlet, an outlet for a suction current and a feather outlet, an exhaust device, suction conduits leading from said current outlet and said feather outlet to the suction side of said exhaust device, an air box interposed in the conduit leading from said feather outlet and having a valve-controlled air inlet, and a discharge-box connected to the delivery side of said exhaust device and having a valve-controlled outlet.
8. A feather renovator comprising a treating chamber having a feather inlet, an outlet for a suction current and a feather outlet, an exhaust device, suction conduits leading from said current-outlet, and said feather outlet to the suction side of said exhaust device, an air box interposed in the conduit leading from said feather outlet and having a valve-controlled air inlet, a discharge-box connected to the delivery side of said exhaust device and having a valve-controlled outlet, and a transferable spout applicable to the inlet of said air box or the outlet of said discharge box.
9. A feather renovator, comprising a treating chamber having a feather inlet, a feather outlet in the lower portion of said chamber, and an outlet for down in its upper portion, an exhaust device, and suction conduits leading from said feather and down outlets to said exhaust device.
10. A feather renovator, comprising a treating chamber having a feather inlet, an outlet for a suction current opposite said inlet, a feather outlet in the lower portion of said chamber and an outlet for down in its upper portion, an exhaust device, a conduit connecting said feather outlet with said exhaust device and having a cut-off valve, a main suction conduit leading from said suction-current outlet to said exhaust device, a branch conduit leading from said down outlet to said main suction conduit, and cut-off valves arranged in said main and branch suction conduits.
11. A feather renovator, comprising a treating chamber provided in its top with an outlet for down, a hood arranged over said down outlet, an exhaust device, and a suction conduit leading from said hood to said exhaust device.
12. A feather renovator, comprising a treating chamber provided in its lower portion with a feather outlet and in its top with an outlet flue for down, said flue having a damper, a hood arranged over the upper end of said flue, an exhaust device, and suction conduits leading from said hood and said feather outlet to said exhaust device and each having a cut off valve.
